(57) **CLAIM**

The ornamental design for a ring capsule, as shown and described.

DESCRIPTION

FIG. 1 is a front, left, bottom perspective view of a ring capsule disassembled into an inner piece and an outer piece, showing the new design;

FIG. 2 is a front, right, top perspective view thereof;

FIG. 3 is a rear, bottom perspective view thereof;

FIG. 4 is a rear, top perspective view thereof;

FIG. 5 is a front view of the ring capsule of FIG. 1 in a first alternative orientation;

FIG. 6 is a front, top perspective view thereof;

FIG. 7 is a rear, top perspective view of the ring capsule of FIG. 1 in a second alternative orientation;

FIG. 8 is another rear, top perspective view thereof;

FIG. 9 is a front, left side, bottom perspective view of the ring capsule of FIG. 1 in a third alternative orientation;

FIG. 10 is a front, right side, top perspective view thereof; and,

FIG. 11 is a rear view, showing the ring capsule assembled. The broken lines indicate portions that form no part of the claimed design.
